UNITED STATES PATENT OFFICE.

MATHIAS R. KONDOFF, OF ROCHESTER, NEW YORK, ASSIGNOR TO JOHN JACOBS, OF MERION, PENNSYLVANIA.

METHOD OF PACKING BOTTLES.

1,378,356.

Specification of Letters Patent. Patented May 17, 1921.

Application filed October 27, 1917. Serial No. 198,851.

To all whom it may concern:

Be it known that I, MATHIAS R. KONDOFF, a citizen of the United States, residing at Rochester, in the county of Monroe and State 5 of New York, have invented certain new and useful Improvements in Methods of Packing Bottles, of which the following is a specification.

The object of this invention is to provide 10 a new and improved method for packing bottles or other articles in a box for shipping and to make a package in which bottles or other articles are packed by such improved method.

15 This and other objects of the invention will be fully illustrated in the drawings and described in the specification and pointed out in the claims at the end thereof.

In the drawings,

20 Figure 1 is a top plan view of the tapered box shown in Fig. 4 with the bottles packed therein according to my invention, the lid being omitted.

Fig. 2 is a perspective view of a serpentine 25 packing strip.

Fig. 3 is a top plan view of the tapered box shown in Fig. 1 with the sides drawn to parallel position.

Fig. 4 is a vertical transverse section taken 30 on the line 4^x—4^x of Fig. 1.

Fig. 5 is a top plan view of a square box packed according to my invention.

Fig. 6 is a vertical transverse section taken 35 on the line 6^x—6^x of Figs. 3 and 5.

In the drawings like reference numerals indicate like parts.

In the drawings reference numeral 1 indicates a paper box preferably built with tapering side walls. In this box I have arranged 40 a series of layers of bottles 2 such as are shown in section in Fig. 4, the top row or layer of bottles being shown in Fig. 1. These layers will be referred to by the reference characters A, B and C, and the bottles 45 of each row may be referred to by numerals 2, 3, 4 and 5.

The bottles of each row while shown to be four in number may be of any other number desired and the number of layers of bottles 50 may be any number other than three as may be desired.

The bottles contained in this package are of usual form being made with large bodies and small necks and the bottles in each row 55 are arranged with the neck and body of ad-

jacent bottles reversed and nested with each other, the neck of each of the intermediate bottles being nested between the bodies of the two adjacent bottles, the shoulders of consecutive bottles being held apart leaving 60 a space between them; that is, only partially filled by the thickness of the packing strip that will now be described.

The bottles in each row are held in place by a serpentine strip 6 made preferably of 65 cardboard or similar material which strip is preferably made in width somewhat less than the diameter of the body of the bottle and somewhat more than the diameter of the neck of the bottle. This strip need not be 70 of uniform width throughout its length. This strip is shown in Figs. 1 and 3 with the ends thereof lapped around the bases of the outside bottles of the layer. The strip passes from the base of the first bottle of the 75 layer along the length of the bottle and parallel to the side of the box and makes a close fit between the body of the bottle and the side of the box. From a point opposite the head of the bottle, it bends at right angles 80 to itself and passes over the head of the bottle and makes contact therewith, making contact with the body of the second bottle, bending reversely to pass between the neck of the first bottle and body of the second 85 bottle. From this point it passes between the first and second bottles to the head of the second bottle around which it laps making contact at points opposite to the head of the second bottle with the bodies of the 90 first and third bottles. In like manner it follows the space between the bottles from the head of each bottle to the head of the next bottle through the series, finally passing along the length of the end bottle, the 95 end of the strip laps the base of the end bottle.

The first and last longitudinal sections of the serpentine strip are substantially as long as the length of the bottles and the intermediate longitudinal sections of the serpentine strip are considerably shorter, being only long enough to reach between the heads of consecutive bottles as they are placed with the necks and bodies of adjacent bottles reversed and nested with each other.

The transverse sections of the serpentine strip which connect the longitudinal sections thereof are of sufficient length to properly space the bodies of the bottles laterally and 110

the length of the longitudinal sections is sufficient to space the bottles longitudinally. The box and the serpentine strip are both proportioned to the size of the bottles that 5 will be contained in the box. The bottles and the strip when assembled will make a close fit with the box and the strip will make a close fit with the bodies of the bottles.

It will be seen by an inspection of Figs. 10 3 and 5 that the strip bends at the shoulder of each bottle where the body ends and the neck begins, and runs practically straight from the shoulder of one bottle to the shoulder of the next. The bottles are held from 15 coming into contact at points on the strip directly opposite to each other. Such contact is to be avoided for if it were otherwise a sudden jar to the package would be communicated from one bottle to the next 20 through the serpentine strip with such force as to possibly crack or break the bottle.

Below each row of bottles is placed a 25 layer of packing material 7, which is shown as made of corrugated paper. This corrugated paper where the bottles overlap each other will bend around and partially conform to the shape of the bodies of the bottles, which bottles will thereby be the more securely held in place and held against 30 movement.

The bottles of each row are reversed with 35 relation to the adjacent bottle or bottles of the row above or below. That is, in each column of bottles in the package when it is complete, the neck of each of the intermediate bottles is nested between the bodies of the bottles directly above and below it. Over the top row of bottles is placed a 40 layer of packing material 8 which layer may be fastened in the cover of the box.

The width or height of the transverse sections of the serpentine strip is such that when the box is packed the weight of the body of each bottle above the bottom row 45 will rest on the transverse section of the strip below it and will be supported thereby.

The serpentine strip will be cut out of 50 flat stock and then scored and bent up by hand to the desired shape before being placed in the box, after which the bottles will be placed therein.

The dimensions of the box and the serpentine strip are proportioned to hold the bottles in the correct position with relation to each other so that when they are 55 pressed together each bottle will press against and draw the intermediate longitudinal sections of the serpentine strip up tight and press against them at two or more points, one of which will be intermediate the points where the next adjacent bottle will press.

The strip is sufficiently stiff so that it will assist, by its own resistance to conforming 60 to the contour of the bottles, in separating

and cushioning the bottles against blows or pressure.

As the strip will be under tension in the direction of its length the bottles will be held from making contact with each other because they are held in suspension thereby. In this manner the bottles are spaced properly and cushioned against pressure or a blow from any direction.

It will also be understood that similar 75 serpentine strips can be used running vertically through the package supporting each column of bottles.

Though for the purpose of describing my invention herein I have confined myself to 80 its use in the packing of bottles, it will be understood that many other articles may be packed in this manner to advantage.

After the box with tapering sides has been packed as shown in cross section in Fig. 2, the sides of the box are drawn into substantially parallel position and held in such position by the cover of the box in substantially the same manner as has been described in my Patent No. 1,234,480. When the sides 90 are drawn into parallel relation, the bottles of each row will be drawn closer together so that the intermediate longitudinal sections of the serpentine strip will press firmly against the bodies of the bottles 95 in the manner indicated in Fig. 3.

The box with tapering sides is packed more easily than the box with parallel sides and when the sides are drawn up to parallel 100 position, the package will be almost the same as though it had originally been packed in a box having parallel sides.

Many changes may be made in the foregoing without departing from the spirit of 105 my invention.

Each end of the serpentine strip may be extended to pass by the bottoms of all the bottles of the layer on the one side of the box, by which it will be the more securely fastened, or it may be cut short of lapping the end of the outside bottle and it may be fastened to the wall of the box at the side of the bottle in any suitable manner.

The edge of the serpentine strip may be fastened in any way to the pad or packing sheet that separates the rows or layers of bottles if so desired, or the packing sheet between the layers may be omitted, in which case the bodies of the bottles will rest directly on the transverse sections of the serpentine strip.

The bottles may be packed so that each bottle stands vertically with or without the pad between the rows, in which case one half of the bottles would stand upright and the other half would be inverted. The upright bottles would be put in first, the pads, if used, would then be placed between the rows, the serpentine strips would then be inserted over the heads of the upright bot- 130

bles and the other half of the bottles would then be put in place inverted into the openings left between the upright bottles from which they would be spaced apart by the 5 serpentine strips.

I claim:

1. A package which consists of a container, a row of articles placed therein, said articles being nested with each other and a 10 serpentine strip, having its ends anchored, separating and spacing the said articles and adapted to be drawn close around the sides of said articles, said strip being placed under tension by the insertion of the said articles in the package.
2. A package which consists of a container, a row of articles placed therein, said articles being nested with each other and a serpentine strip, having its ends anchored 20 to the container, separating and spacing the said articles and adapted to be drawn close around the sides of said articles, said strip being placed under tension by the insertion of the said articles in the package.
- 25 3. A package which consists of a container, a row of articles placed therein, said articles being nested with each other and a

serpentine strip, having its ends adapted to lap the base of the outer articles of the row and in coöperation with the container be 30 anchored to the container, said strip separating and spacing the said articles and adapted to be drawn close around the sides of said articles, said strip being placed under tension by the insertion of the said articles in the package.

4. The method of packing articles in a container which comprises the initial placing of the exterior articles to anchor the 40 ends of a separating strip and thereafter inserting the remaining articles in suitable pockets formed by bends in said strip, the insertion of the last article serving to place the strip under tension and hold the articles in suspension.

5. The method of packing articles in a container which comprises the insertion of the articles within pockets formed by a serpentine strip passing through the container with its ends held, the insertion of the last 50 article serving to place the strip under tension and hold the articles suspended apart.

In testimony whereof I affix my signature.
MATHIAS R. KONDOLF.
